Inventor
ERNEST V. JUNGK.
by his attorney
Herbert H. Thompson

UNITED STATES PATENT OFFICE.

ERNST V. JUNGK, OF BROOKLYN, NEW YORK, ASSIGNOR TO EMIL W. YOUNG, OF BROOKLYN, NEW YORK.

WASHER.

Application filed September 12, 1921. Serial No. 500,127.

To all whom it may concern:

Be it known that I, ERNST VICTOR JUNGK, a citizen of the United States of America, residing at 442 Autumn Avenue, Brooklyn, 5 in the county of Kings and State of New York, have invented certain new and useful Improvements in Washers, of which the following is a specification.

This invention relates to washers or bushings designed to be applied for example, to the shafting of machinery, or to the shackle bolts on motor cars between the shoulder and the nut for taking up play between said parts, without the removal of the nut or 15 other holding member.

The object of my invention is to improve upon washers of this description so that the two parts of the washer may be applied without loosening the bolt or at least without 20 loosening it more than the thickness of the washer, and at the same time to design a washer so that the two parts will be permanently locked together when once applied.

Further objects of the invention will appear as the description proceeds.

Referring to the drawing in which what I now consider to be the preferred forms of my invention are shown, Fig. 1 is a plan view of a removable washer constructed according to my invention showing the key to one side,

Fig. 2 is a plan view of the same showing it in the act of being applied to a bolt or shaft, but before the key has been driven 35 home.

Fig. 3 is a corresponding view after the key has been driven and locked into place.

Fig. 4 is a section on line 4—4 of Fig. 1.

Fig. 5 is a detail view of a slightly modified form of key.

The main or body portion of my two part washer is shown at 1, while the key is shown at 2. The body portion is provided with the usual central circular aperture 3 the walls 45 of which merge into the parallel side walls 4 and 5 of the lateral opening 6 permitting the washer to be inserted over the shaft or bolt 7 as will be readily apparent. At least one of said parallel and preferably each wall 50 is provided with a recess or notch 8, 8', which extends beyond the periphery of the recess 3 to receive the prongs 9, 10 of key 2 as herein-after explained.

The key portion has parallel sides 13 and 55 14 and is preferably curved on outer rim or

edge to the same diameter as the periphery of body portion 1. The inner portion of the key is recessed to form one or more prongs 9 and 10. While said recess need not be circular, the radius of curvature of the same is 60 less than the radius of the bolt 7 or of aperture 3, or in other words the distance *a* (Fig. 1) between the inner ends of the prongs 9 and 10 is less than the diameter or cord *b*, so that the prongs engage the bolt 7 as the key 65 is slid radially into place (Fig. 2). The key is then struck with a hammer preferably, until the prongs are forced outwardly into notches 8, 8' and the key is flush with the washer (Fig. 3).

In Fig. 5, a slightly modified form of key 2' is shown wherein the ease with which the key may be driven into place is increased by reducing the thickness of the prongs 9', 10'. The body portion need be varied in no 75 particular since it is not necessary that the prongs completely fill the notches 8, 8' when the key is in place as shown in Fig. 3. All that is necessary is that the prongs or either of them be bent outwardly beyond the parallel edges 13 and 14 to prevent the key from dropping out, as the nut, when tightened will prevent all lateral movement.

Having described my invention what I claim and desire to secure by Letters Patent 85 is:

1. A two part washer comprising an annular body portion having an opening in one side adapted to receive a bolt or shaft, a wall of said opening having a recess therein, and a key member having a recessed inner portion forming a prong on a side thereof adapted to be expanded outwardly into said recess by said bolt or shaft as the key is driven home.

2. A two part washer comprising an annular body portion having an opening in one side adapted to receive a bolt or shaft, the walls of said opening having opposite recesses therein and a key member having a prong on each side thereof, the ends of which are of less distance apart than the chord across said bolt or shaft between the points where the prongs engage the same, whereby said prongs are swaged outwardly 105 into said recesses by said bolt or shaft as the key is driven home.

3. As an article of manufacture, a take up washer or bushing comprising a body portion with the usual central circular opening 110

and cut away on one side on parallel lines to form an opening for insertion of the bolt or shaft, said parallel walls having notches therein, and a flat key having parallel sides 5 for insertion into said opening and a recess at its inner portion forming opposite prongs, the radius of curvature of said recess being less than the radius of said circular opening, whereby said key engages said bolt or 10 shaft as it is forced into place and the opposite prongs are bent outwardly into said notches.

4. As an article of manufacture, a take up washer or bushing comprising a body 15 portion with the usual central circular opening and cut away on one side to form a lateral opening having walls for the insertion of the bolt or shaft, said walls having portions thereof spaced farther apart than 20 the entrance to said lateral opening, and a flat key having straight sides for insertion into said opening and a recess at its inner

portion forming opposite prongs, the radius of curvature of said recess being less than the radius of said circular opening, whereby 25 said key engages said bolt or shaft as it is forced into place and the opposite prongs are bent outwardly into spaced apart portions.

5. A two part washer comprising an annular body portion having an opening in one side adapted to receive a bolt or shaft, the walls of said opening having opposite recesses therein, and a key member having a prong on each side thereof, the ends of 30 which are of less distance apart than the chord across said bolt or shaft between the points where the prongs engage the same, whereby said prongs are expanded outwardly into said recesses by said bolt or shaft 40 as the key is driven home.

In testimony whereof I have affixed my signature.

ERNST V. JUNGK.
